US00D791155S

(12) **United States Design Patent** (10) **Patent No.:** **US D791,155 S**
Segars (45) **Date of Patent:** **** Jul. 4, 2017**

(54) **DISPLAY SCREEN WITH COGNITIVE COMMERCE PERSONAL SHOPPER TRAINER ACCESS GRAPHICAL USER INTERFACE**

(71) Applicant: **Cognitive Scale, Inc.**, Austin, TX (US)

(72) Inventor: **Joshua L. Segars**, Cedar Park, TX (US)

(73) Assignee: **Cognitive Scale, Inc.**, Austin, TX (US)

(**) Term: **15 Years**

(21) Appl. No.: **29/541,035**

(22) Filed: **Sep. 30, 2015**

(51) **LOC (10) Cl.** **14-04**

(52) **U.S. Cl.**

USPC **D14/486**
